UNITED STATES PATENT OFFICE.

EUGENE BROWN, OF COLFAX, WASHINGTON.

CONCRETE-MIXER.

1,314,124.

Specification of Letters Patent. Patented Aug. 26, 1919.

Application filed March 24, 1916. Serial No. 86,485.

To all whom it may concern:

Be it known that I, EUGENE BROWN, a citizen of the United States, residing at Colfax, in the county of Whitman and State of Washington, have invented a new and useful Concrete-Mixer, of which the following is a specification.

This invention relates to concrete mixers, one of its objects being to provide a tilttable drum with which is combined a carriage mounted in a novel manner and having special means whereby, when the drum is tilted, the carriage is caused to move toward and from the drum along a track provided therefor, thereby to direct a delivery chute into and out of the drum.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

30 In said drawings:

Figure 1 is a side elevation of the machine, the drum being shown tilted to discharging position.

Fig. 2 is a plan view, the drum being shown in horizontal position.

Fig. 3 is a section through a portion of the machine and showing the drum in upwardly inclined or receiving position.

Fig. 4 is a section on line A—B Fig. 3.

40 Fig. 5 is an elevation of the outer end portion of the feed chute, its supporting platform being shown in section.

Fig. 6 is a perspective view of the coöperating portions of one side of the wheel supported structure and its extension platform, said parts being detached from each other.

Fig. 7 is a side elevation of a portion of the barrel rotating mechanism at the side 50 of the machine opposite to that shown in Fig. 1.

Referring to the figures by characters of reference 1 designates a wheel supported structure having a motor (not shown) which 55 is preferably arranged within a housing 2,

the said motor driving a shaft 3 from which motion is transmitted through a pulley 4 and belt 5 to a pulley 6 secured to a short shaft 7 journaled upon one side portion of the structure 1. Secured to this shaft so as 60 to rotate therewith and with the pulley 6 is a sprocket 8 for the purpose hereinafter set forth.

Arranged within the upper portion of the structure 1 are side strips 9 having trunnions 10 alining with the shaft 7 and which trunnions are journaled on the structure 1. Side strips 9 are connected at their ends by means of cross strips 11, to the sides of rectangular frames 12 on which are journaled 70 anti-friction rollers 13. In the lower corner portions of these frames are journaled supporting rollers 14. Journaled upon the upper cross strips 11 is a transverse shaft 15 to which is secured a sprocket 16 adapted to receive motion through a chain 17, from the sprocket 8 on shaft 7. A bevel gear 18 is secured to the shaft 15 and meshes with a gear 19 secured to a shaft 20 which is journaled on one of the frames 12 and also upon an extension frame 21 which is secured to said frame 12 and moves therewith. A sprocket 22 is secured to the shaft 20 and is adapted to transmit motion through a chain 23 to a sprocket 24 secured to a stud 25 extending at right angles from a plate 26. This plate is adapted to be attached to head 27 of a wooden barrel 28, one end of the barrel being open and said barrel being extended through the frame 12. Detachably 90 mounted on the barrel at opposite sides of the center thereof are rings 29 having inwardly extended flanges, said rings being preferably made of T-irons. Bolts 30 connect the rings and are arranged between the wall of the barrel and the inwardly extending flanges on the rings. Said inwardly extending flanges are adapted to be engaged by the supporting rollers 14 and by additional side rollers 31 connected to the sides 95 of the frames 12. The rollers 13 bear against the outwardly extending portions of the rings. Thus the various rollers provide antifriction bearings for the barrel so that said barrel can rotate freely within the frame and will, at the same time, be held against longitudinal displacement relative thereto.

A shaft 32 is journaled in the structure 1 and is provided with radial arms 33 and 110

with an actuating lever 34. The arms 33 are connected to the extension frame 21 by links 35 and thus it will be seen that when lever 34 is shifted in one direction the extension frame 21 will be swung upwardly, thereby to lower the open end of the barrel whereas, when lever 34 is swung in the opposite direction, the extension frame 21 will be lowered and the open end of the barrel 10 will be raised.

Extending from the wheel supported structure 1 is a platform 36 which may be provided with hinged supporting legs 37 having casters 38. Any suitable means, such as rods 39, may be employed for bracing the legs while the said platform is set up for use. This platform can be detachably connected to the frame 1 in any suitable manner or it can be made integral therewith. If detachably connected, each of the sides thereof is formed with a socket member 40 the sides of which converge upwardly and which socket member is adapted to engage a hook or projection 41 connected to the side portion of the structure 1. By lifting up on the sides of the platform 36, the same can be disengaged from the projections 41.

Secured on the platform 36 are parallel angle strips 42 forming rails designed to support rollers 43. These rollers support a carriage 44 carrying a chute 45 which is inclined downwardly toward the barrel 28. Rods 46 are pivotally connected to the carriage and to opposed portions of the barrel 28 close to the open end of the barrel so that, when the barrel is swung downwardly at its open end, it will thrust through the rods against the carriage, thus to shift the carriage away from the barrel whereas, when the barrel is raised at its open end, the rods 46 will pull upon the carriage and direct the lower or discharge end of the chute into the open end of the barrel as shown particularly in Fig. 3.

In using the apparatus the platform 36 is assembled with the structure 1 and the barrel 28 is adjusted so that its open end will be elevated. The motor is then set in motion so as to drive through the belt 5 and pulley 6 and through the sprocket 8, chain 17, and sprocket 16 to the shaft 15 which, in turn, transmits motion through the gears 18 and 19, shaft 20, sprocket 22, and chain 23 and sprocket 24 to the barrel. This barrel will thus be rotated in the frames 12, the rollers 13, 14 and 31 serving to reduce friction to the minimum. While the barrel is being rotated, the various materials to be mixed are discharged into the

chute 45 which, at this time, is projecting into the barrel as shown in Fig. 3. After a sufficient amount of material has been deposited in the rotating barrel and the material has been properly mixed, lever 34 is swung to its other extreme position with the result that the barrel while still rotating will be brought to the position illustrated in Fig. 1. During this tilting of the barrel the chute 45 will be moved backwardly away from the barrel. After the contents of the barrel have been discharged, said barrel can be brought back to its initial position, this action causing the chute 45 to reenter the barrel, the parts thus being in position for mixing another batch.

It has been found in practice that a wooden barrel is not only cheaper than a metal one, but lasts just as long and, as a matter of fact, constitutes a better mixer for the reason that a greater amount of friction is set up with the result that the material is thrown over more effectively. Furthermore as the barrel wears out it can be readily removed simply by disconnecting the rings 29 from each other, by detaching the plate 26, and by then slipping the barrel longitudinally from the frames 12. A new barrel can then be placed in the frames, the rings placed therearound and fastened, and the plate 26 quickly attached to the closed end of the barrel whereupon the machine will be ready for further use.

What is claimed is:

A concrete mixer including a support, a tiltable frame carried by the support, a drum rotatable in the support, said drum being open at one end, means for rotating the drum, parallel rails mounted on the support and extending close to the path of movement of the open end of the drum, a carriage movably mounted on said rails for reciprocation, rods pivotally connected to the carriage and to the drum close to the open end thereof, means for tilting the drum to move the carriage toward the drum when the open end is lowered into filling position and to move the carriage away from the drum when the said end of the drum is raised, and a chute upon the carriage, movable into and out of the open end of the drum.

In testimony that I claim the foregoing as my own, I have hereto affixed my signature in the presence of two witnesses.

EUGENE BROWN.
